ATTORNEY

UNITED STATES PATENT OFFICE.

STEWART S. SWOYER, OF LOS ANGELES, CALIFORNIA.

THEATRICAL TRICK-PERFORMING PLATFORM.

Application filed December 20, 1926. Serial No. 155,876.

This invention relates to apparatus to be used in the theatrical profession, particularly by vaudeville performers whose acts are featured or accompanied by acrobatic 5 stunts or tricks.

One of the tricks performed by myself during the presentation of my present act is to start to run up one edge of the proscenium arch of the theatre and terminate the 10 run by a somersault or back flop. This trick is very effective but in some theatres the arches are not located with respect to the foot light trough and the stage so as to enable the trick to be done, and in other 15 theatres the managers raise objections to the performance of the trick on the ground that the feet of the performer may possibly damage the finish of the arch.

The principal object of my invention 20 therefore is to provide a portable platform to be temporarily mounted in a substantially vertical position just back of the arch at one end thereof and in transverse alinement therewith at the bottom, on which the performer carries out the above mentioned trick 25 and which is so arranged as to give the same effect to the audience as if the performer actually engaged the proscenium arch itself.

A further object of the invention is to provide means for rigidly holding the platform 30 in the desired position and angle so that there is no chance of the device slipping and throwing the performer, while at the same time allowing for instant removal of the 35 platform when the act is finished so as not to interfere in any way with the artists following on the bill. The device is also very light, while rugged and substantial, and is capable of being folded up into a very compact form when not in use so that it may be 40 easily transported from place to place.

A further object of the invention is to produce a simple and inexpensive device and yet one which will be exceedingly effective 45 for the purpose for which it is designed.

These objects I accomplish by means of such structure and relative arrangement of parts as will fully appear by a perusal of the following specification and claims.

In the drawings similar character of reference indicate corresponding parts in the several views:

Fig. 1 is a fragmentary perspective outline 50 of a proscenium arch and stage showing my platform mounted in position relative to the arch.

Fig. 2 is a perspective view of the platform as set up looking from the back thereof.

Referring now more particularly to the characters of reference on the drawings, the 60 numeral 1 denotes the platform itself, a rigid flat rectangular member of suitable dimensions, preferably about 18 inches x 7 feet. The platform is adapted to be set in a comparatively vertical position just back of and 65 close to the proscenium arch 2, so that the lower narrow edge of the platform which rests on the stage 3 is in transverse alinement with the bottom of the arch. The platform is preferably covered on its operating 70 face with rubber or the like so as to provide a non-slip surface for engagement with the feet of the performer.

The platform is supported in the above 75 named position by a pair of legs or supporting members 4 which are pivotally connected to the platform at the back and near the top thereof and which when set up depend toward the floor at a suitable angle to the platform. Intermediate the ends the legs are 80 braced together by diagonal straps 5 or the like and on their lower ends carry downwardly projecting spikes 6 to bite into the floor of the stage, which is always of wood.

The platform and legs are connected together intermediate their ends so as to maintain them in definite angular relation by horizontal hook bars 7 pivoted onto the legs at one end and adapted at their hook ends to engage orificed plates 8 attached to and 85 projecting from the back of the platform.

In order to positively prevent slipping of the platform along the stage when a horizontal operating pressure is applied thereagainst by reason of the contact of the performer therewith, I mount a rigid tongue 9 on the back of the platform at the bottom to detachably enter the opening formed in a socket member 10. This socket member is provided with horizontal side flanges 11 90 which rest on the floor and which are detachably secured to said floor by suitable means such as lag screws 12. The socket member remains fixed on the floor in its proper position all the time the act is playing at any theatre, but the platform itself is taken down after every performance, merely by tilting the same upwardly to disengage the leg spikes from the floor and then moving the platform forwardly to slip 105 the tongue out of the socket. There is then no interference with the acts of subsequent 110

performers, since the socket member is so small and is so close to the arch that it is not in anybody's way.

It will therefore be seen that when set up 5 the platform is solidly held at the bottom against sliding movement transversely or in a direction away from the application of pressure. The leg members prevent movement of the upper portion of the platform 10 and hold the same rigidly as is necessary. Also the floor engaging spikes prevent the whole apparatus from moving so as to cause the tongue and socket to be disengaged. When the apparatus is taken down the hook 15 bars are disengaged from their orificed plates and the legs are folded against the platform. The device is then in a very compact form, as will be evident, so that it may be easily transported.

20 The positioning of the platform relative to the arch is such that an illusory effect on the audience is obtained, and said audience imagines that the actor performing the tricks 25 on the platform is in reality using the proscenium arch. If desired, in order to disguise the platform and render the same practically indistinguishable from any angle in front, I may paint or otherwise color the exposed surface of the platform the same as 30 the adjacent surface of the arches of different theatres.

From the foregoing description it will be readily seen that I have produced such a device as substantially fulfills the objects of 35 the invention as set forth herein.

While this specification sets forth in detail the present and preferred construction of the device, still in practice such deviations from such detail may be resorted to as do not form 40 a departure from the spirit of the invention, as defined by the appended claims.

Having thus described my invention what

I claim as new and useful and desire to secure by Letters Patent is:

1. A theatrical platform for trick-performing operations comprising a platform element to stand in a substantially upright position from a stage floor and adapted to support the weight of a performer thereon, legs depending from the back of the platform to the floor at an angle to the platform, and disconnectable latching means between the floor and platform for preventing sliding movement of the platform in a direction away from the front face of the same. 45 50 55

2. A theatrical platform for trick-performing operations comprising a platform element to stand in a substantially upright position and adapted to support the weight of a performer thereon, legs depending from the back of the platform at an angle thereto, spikes projecting downwardly from the bottom of the legs, to engage the floor and prevent sliding of the legs along the floor, and additional disengageable latching means between the floor and platform for holding the latter against movement in a certain direction. 60 65

3. A theatrical platform for trick-performing operations comprising a platform element to stand in a substantially upright position from a stage floor and adapted to support the weight of a performer thereon, means for supporting the platform in such position, and means for detachably holding the platform against movement along the floor in one direction, such means comprising a socket member adapted to be secured to the floor adjacent and at the back of the platform, and a tongue fixed on the back of the platform to detachably engage the socket. 70 75 80 85

In testimony whereof I affix my signature:
STEWART S. SWOYER.
